UNITED STATES PATENT OFFICE.

JAMES H. BEARDSWORTH, OF LYNN, MASSACHUSETTS.

CLOTHES-DRIER.

SPECIFICATION forming part of Letters Patent No. 616,880, dated January 3, 1899.

Application filed February 6, 1897. Serial No. 622,258. (No model.)

To all whom it may concern:

Be it known that I, JAMES H. BEARDSWORTH, a citizen of the United States, residing at Lynn, in the county of Essex and State 5 of Massachusetts, have invented certain new and useful Improvements in Clothes-Driers; and I do hereby declare the following to be a full, clear, and exact description of the invention, such as will enable others skilled in the 10 art to which it appertains to make and use the same.

My invention relates to improvements in clothes-driers; and the object of the same is to provide a clothes-drier for house use, the 15 same being adapted for attachment to the wall out of the way, and when desired for use may be lowered to receive the clothes and then raised to any desired position for drying the same.

20 The invention consists of the details of construction hereinafter fully described and claimed.

In the accompanying drawings, forming a part of this specification, Figure 1 is a view 25 of my device in the lowered position. Fig. 2 is a view of the same when elevated. Fig. 3 is a view of the drier when closed; and Fig. 4 is a section through one of the recesses of the securing-head, showing the clothes-receiving 30 arm positioned therein.

Referring now to said drawings, 1 indicates the frame, which is closed at one end and adapted to be attached to the wall by screws or other similar devices. The inner sides of 35 the side pieces 2 of the frame are provided with grooves 3, and adapted to slide in this frame 1 is the standard 4, the flanges 5 of the said standard taking the grooves 3 of the frame.

40 The side pieces 2 are secured together and braced by the straps 2', which are attached on the rear sides of said side pieces. Secured to the upper end of the standard 4 is a circular head 6, which is composed of the concentric 45 semicircular walls 7 and 8, which are connected by the downwardly-curved partitions

9. These partitions 9 divide the head into a number of recesses 10. The clothes-receiving arms 9' are adapted to depend vertically 50 through the recesses 10, when closed, as illustrated in Fig. 3, the enlargements 10' on the

outer ends preventing their slipping entirely therethrough. On the inner ends of the arms are the pins 8', which are adapted to project behind the wall 8 of the head when the arms 55 are positioned for receiving the clothes, the lower edge of the arm resting upon the lower wall 7 of the head, as illustrated in Fig. 4. The arms are thus prevented from being removed from the head by the engagement of 60 the pins with the upper wall and are supported by the lower wall of the head. The head is attached to the standard by screws passing through the perforated lugs 11', 65 formed on the rear face of the head.

The pulleys 11 are mounted at the upper end of the frame 1, and the upper end of the standard 3 is provided with a pulley 12. A rope 13 is secured at one end of the standard 3 and passed around the pulleys 11 and 12, as 70 illustrated. The lower end of this rope is adapted to be wound upon the hook 14 at the lower end of the frame 1.

The standard is provided at its lower end upon its front face with the finger-hold 1', by 75 means of which the standard may be moved by the hand. As illustrated in Fig. 1, when not desired for use the standard and the clothes-receiving arms may be elevated to the top of the frame and out of the way. When 80 it is desired to use the device, the standard is lowered and the clothes placed on the clothes-receiving arms, when the same may be raised to any desired position. When not in use, the arms may be folded, as illustrated 85 in Fig. 3.

From the above description it will be seen that I have produced a very simple and convenient device for drying clothes, whereby the clothes may be raised to the top of the 90 room, where a greater amount of heat is always present, whereby the drying is much more readily accomplished and the clothes are out of the way.

Having thus described my invention, what 95 I claim as new, and desire to secure by Letters Patent, is—

In a clothes-drier, the combination of a frame composed of grooved side pieces 1 and 2, a cross-piece which connects the side pieces 100 at their upper ends and also acts as a stop for the standard, a strap on the back of the frame

for connecting the free ends of the side pieces and holding them in fixed relation, a standard having flanges arranged to work in the grooves in the side pieces and to strike the 5 cross-piece when raised to its extreme position, a head attached to the standard for supporting the clothes-receiving arms, the head comprising a single casting having two semi-circular concentric walls which are connected 10 by partitions, clothes-receiving arms mounted on the head between the partitions, a pin on each arm to prevent its removal, a pulley se-

cured to the cross-piece of the frame, a second pulley secured to the standard, and a cord for adjusting the position of the standard with 15 respect to the frame.

In testimony whereof I have signed this specification in the presence of two subscribing witnesses.

JAMES H. BEARDSWORTH.
